HANDLE FOR A CIRCUIT BREAKER
OR THE LIKE

Wolfgang E. Wilckens, Johannesburg, Transvaal, Republic of South Africa, assignor to Heinemann Electric Company, Trenton, N.J., a corporation of New Jersey

Filed Aug. 9, 1966, Ser. No. 3,401

Term of patent 14 years

(Cl. D26—13)

Fig. 1.

Fig. 2.

Fig. 3.

FIG. 1 is a front perspective view of a handle for a circuit breaker or the like showing the new design;

FIG. 2 is a side elevational view showing the handle in the "off" position; and

FIG. 3 is an enlarged top perspective view thereof.

The dot-dash line shown in the drawing disclosure is for illustrative purposes only.

I claim:

The ornamental design for a handle for a circuit breaker or the like, as shown and described.
